UNITED STATES PATENT OFFICE.

DWIGHT S. RICHARDSON, OF NEW YORK, N. Y.

DESIGN FOR A FURNACE-BODY.

SPECIFICATION forming part of Design No. 30,681, dated May 2, 1899.

Application filed February 20, 1899. Serial No. 706,258. Term of patent 14 years.

To all whom it may concern:

Be it known that I, DWIGHT S. RICHARDSON, a citizen of the United States, residing at New York, in the county of New York and State of New York, have invented a new and original Design for Bodies of Fuel-Burning Furnaces, of which the following is a specification, reference being had to the accompanying drawings, forming part thereof.

10 In said drawings, Figure 1 is a perspective elevation of the body of a furnace embodying my present design. Fig. 2 is a top plan view of the same.

15 Like letters of reference in both figures refer to the same parts.

As shown in the drawings, the leading and material feature of my present design is the body portion, having a central dome of hemispherical or curved contour, with the fuel-opening projection at one side thereof and the smoke-exit at the opposite side thereof.

20 The letter A indicates the dome of the body

portion, having the curved or hemispherical contour and substantially circular in cross-section at the base, as illustrated in Fig. 2. 25

B indicates a forwardly-extending horizontal projection forming the fuel-supply opening, and C a diagonally upwardly-extending projection forming the smoke-exit opening, said projections being arranged on substantially opposite sides of the body portion A.

Obviously the design is applicable to fuel-burning furnaces generally, although especially designed for use in connection with 35 domestic hot-air furnaces.

Having thus described my invention, what I claim is—

The design for a furnace-body herein shown and described.

DWIGHT S. RICHARDSON.
